UNITED STATES PATENT OFFICE.

GEORGE BROWN, OF BOSTON, MASSACHUSETTS.

FOLDING COUCH.

SPECIFICATION forming part of Letters Patent No. 623,593, dated April 25, 1899.

Application filed October 29, 1898. Serial No. 694,906. (No model.)

To all whom it may concern:

Be it known that I, GEORGE BROWN, of Boston, county of Suffolk, and State of Massachusetts, have invented an Improvement in Folding Couches, of which the following description, in connection with the accompanying drawings, is a specification, like letters on the drawings representing like parts.

The present invention relates to a folding or convertible couch and is embodied in a couch having a jointed supporting-frame at each end and a bed-spring extending from one frame to the other, the jointed portions of the frame constituting lateral folding extensions which normally hang vertically at the sides of the couch, but are capable of being brought to a horizontal position to widen the couch and adapt it for use as a bed.

The present invention relates mainly to the means for locking the extensions or wings in their extended position, the locking devices being independent of each other, so that either or both wings can be moved to a horizontal position, as desired, one object of the invention being to provide the couch with locking mechanism which can be easily operated from either end of the couch.

A further object of the invention is to simplify the construction, so that the wings may be easily manipulated, while the couch may be inexpensively constructed.

A further feature of the invention consists in providing the spring (which is of that type in which a number of parallel links are connected together and secured to the ends of the couch by means of spiral springs) with an additional link, so that one spiral spring will be at the extreme edge of the fixed portion of the frame and another immediately adjacent thereto at the extreme edge of the wing portion, both of said springs being connected with the same line of links, the object of this being to cause the spring as a whole to bend at a sharp angle instead of rounding over. The spring in the complete couch is intended to be covered by a cushion or mattress, the said mattress, however, not being shown herein, since it forms no part of the invention.

Figure 1 is a side elevation, with parts broken away and shown in section, of a couch-frame embodying the invention. Fig. 2 is a

section on line x^2 of Fig. 1, looking toward the left; and Fig. 3 is a detail in plan, showing the means for connecting the spring with the main frame and side wings.

The main frame of the couch comprises the end members a , provided with legs a^2 , the said end members being connected together by longitudinal frame members or angle-irons b , extending from one to the other and connected therewith in any suitable or usual way. The spring c , which consists of a number of links suitably connected together, is stretched between the said end members and is connected by means of spiral springs c^2 with angle-irons or transverse frame members c^3 , which extend across the couch above the members b and are bolted or otherwise secured to brackets d , which are connected by bolts d^2 with the angle-irons b and end members a , respectively, the said brackets having strengthening-ribs d^3 , as shown in Figs. 1 and 2. The transverse angle-irons c^3 are provided with extensions c^4 , pivotally connected therewith, and thereby constitute jointed supporting-frames for the spring, the pivotal connection being afforded, as herein shown, through the agency of the brackets d , which are provided with bolts d^20 , passing through suitable openings in the wings c^4 and forming hinges or pivots therefor. The spring c is also connected with the said wings, so that when the said wings are in their horizontal position, as shown in Fig. 2, the full width of the spring is stretched and the couch is practically converted into a bed. To afford the necessary strength, the wings c^4 at each end of the bed are connected together by angle-irons c^5 , extending longitudinally from one to the other, the said angle-irons being shown as directly secured to brackets c^3 and connected, as by bolts or rivets c^7 , with the said extensions c^4 . To lock the wings in either their vertical or their horizontal position, each wing is provided with an arm e , pivotally connected therewith at c^8 and supported at its opposite end in an extension d^1 of the bracket d , said arms extending downward toward the frame members b , to which are connected locking-levers, which cooperate with said arms, as will be described. The said arms e are provided with locking-shoulders e^1 and retaining-notches e^2 , arranged to be re-

spectively engaged, according to the position of the wings, by the locking-levers f , pivoted at f^2 on the angle-irons b , the longer ends of the levers lying in contact with the arms e , so that the said levers will tend to drop behind the shoulders e^4 or into the notches e^5 as the said arms are moved through the brackets. The notches e^5 have inclined walls, as shown, so that they do not prevent the wings from being lifted, but still act to retain them vertically when the couch is folded. As shown in full lines, Fig. 2, one of the wings is in its horizontal position and the lever f is engaged with the shoulder e^4 , thus locking the said extension or wing and holding it horizontal. To fold or convert the bed into a couch, it is necessary only to lift the lever out of engagement with the shoulder, the lever being provided for this purpose with a handle f^3 . When the lever is lifted, it is obvious that the wing will fall by gravity, the arm e traveling through its supporting-bracket until the notch e^5 passes the lever, after which the said lever will drop into the said notch and yieldingly hold the wing in its vertical position. To convert the couch into a bed, on the other hand, it is necessary only to raise the wings by taking hold of the ends thereof until they have been raised far enough to become locked, as shown in Fig. 2, the notches e^5 being so shaped that the levers f will slide out of engagement with the arms e when the wings are lifted. In order that each wing may be independently locked, there is a locking-lever for each one of the four frame extensions c^1 , and the levers which are on one side of the couch are arranged to coöperate, so that a movement of either lever will produce a corresponding movement of the other, whereby one handle only has to be manipulated to unlock the entire wing at one side of the couch. As herein shown, this is accomplished by pivotally connecting the levers f together at f^4 , so that an upward movement produced by the manipulation of the handle f^3 on either lever will be transmitted to the other and produce a corresponding movement thereof.

In bed-springs of the class herein shown the spiral springs c^2 are usually arranged at some little distance apart, generally from two to three inches, and in connecting the joined links which afford the mattress support with the jointed end members utilized in a couch of this class the regular springs will not lie adjacent to each other where the wings adjoin the main portions of the frame-pieces. The consequence of this is that when the

wings are turned down or moved to their vertical position the spring itself will tend to bulge at the sides, and if a reasonably thick mattress or cushion is used the surface of the couch will not be so symmetrical as is desired. The difficulty is obviated in accordance with this invention by connecting one of the spiral springs c^2 with the angle-iron c^6 as nearly as possible at the extreme end thereof and connecting an additional or supplemental spring c^{20} with the wing c^4 at the extreme edge of the same, so that the springs c^2 and c^{20} lie adjacent to each other, the said springs both being connected by links with the same line of links of the jointed portion, while the spring c^{20} is provided with a supplemental link c^{21} for this purpose, as best shown in Fig. 3.

I claim—

1. In a folding or convertible couch, the combination with the couch-body comprising end members and side members, said support having stationary and movable parts pivotally connected together; of a support extending transversely across each end member; a spring stretched from one of said supports to the other; and a locking-rod secured to the movable part of each support and projecting therefrom toward a portion of the frame; engaging shoulders formed on said rods; and a locking-lever for each rod, said levers being pivotally supported on the couch-frame and connected together, substantially as and for the purpose described.

2. In a folding couch, the combination with transverse frame members each provided with one or more extensions pivotally connected therewith, of a mattress-support comprising a number of parallel links joined together, a spiral spring at the end of each line of links to connect the mattress-support with the said transverse frame members and extensions, one of the said springs being connected to one of said parts at a point adjacent to the pivotal connection between said parts, and a supplemental spiral spring connected with the same line of links and with the other part adjacent to the point of connection between said parts, substantially as and for the purpose described.

In testimony whereof I have signed my name to this specification in the presence of two subscribing witnesses.

GEORGE BROWN.

Witnesses:

HENRY J. LIVERMORE,
NANCY P. FORD.

It is hereby certified that in Letters Patent No. 623,593, granted April 25, 1899, upon the application of George Brown, of Boston, Massachusetts, for an improvement in "Folding Couches," an error appears in the printed specification requiring correction, as follows: On page 2, lines 78-80, the comma and the clause "said support having stationary and movable parts pivotally connected together" should be stricken out and inserted after the word "member" and before the semicolon, line 81, as now numbered, same page; and that the said Letters Patent should be read with this correction therein that the same may conform to the record of the case in the Patent Office.

Signed, countersigned, and sealed this 20th day of November, A. D., 1900.
